UNITED STATES PATENT OFFICE.

LAWRENCE E. CASSIDY, OF ARCHER CITY, TEXAS.

INSERT SHIELD AND PROTECTOR FOR SHOE HEELS.

Application filed October 27, 1924. Serial No. 746,189.

To all whom it may concern:

Be it known that LAWRENCE E. CASSIDY, a citizen of the United States of America, residing at Archer City, in the county of 5 Archer and State of Texas, has invented new and useful Improvements in Insert Shields and Protectors for Shoe Heels, of which the following is a specification.

At present, when rubber heels wear down 10 or somewhat loosen, the nails or fastening means which retain the rubber heel to the heel of the shoe work through the heel and prod the foot of the wearer.

It is, therefore, the purpose of the present 15 invention to provide an insert shield or protector for shoe heels to be applied between the heel portion of the continuation of the sole and the main body of the shoe heel proper so that, when fastening the rubber 20 heel to the shoe heel, the nails or other fastening means will strike and clinch on a galvanized sheet iron plate or similar sheet, thereby not only assuring a solid construction but at the same time preventing the 25 fasteners or nails from coming through the insole of the shoe and prodding the foot.

It is to be understood that the particulars herein given are in no way limitative and that, while still keeping within the scope 30 of the invention, any desired modifications of detail and desired proportions may be made in the apparatus according to the circumstances.

The invention comprises further features 35 and combinations of parts to be hereinafter set forth, shown in the drawings and claimed.

In the drawings:

Figure 1 is a sectional view through a 40 portion of a shoe, showing the improved insert shield or heel protector as applied in accordance with the invention.

Figure 2 is a sectional view at right angles to Figure 1.

Figure 3 is a detail perspective view of the insert shield or protector.

Referring to the drawings, 1 designates a shoe provided with a heel 2. Usually in manufacturing shoes, the first lift of the heel is a continuation of the sole of the shoe. It is obvious that the present form of insert shield or heel protector may be manufactured in the heels of shoes at the time of manufacturing the shoes, or may be inserted in the heel subsequently to the construction of the shoe.

During the manufacture of shoes, an insert shield is placed between the first lift of the heel and the adjacent lifts. This insert shield may be any suitable shape and constructed of any suitable sheet metal. Preferably it is dished or arcuate in cross sectional area so as to conform to the slight oval or arcuate shape of the under surface of the first heel lift. In applying the insert 60 shield or protector 3, it is disposed adjacent the under surface of the first heel lift (which is a continuation of the sole of the shoe) and then the successive heel lifts are applied. In order to fasten the successive heel lifts 65 6, the insert shield is provided adjacent its marginal portion with V-shaped cuts or recesses, although they may be of other shapes.

The insert shield is placed in position and then the under surface of the lowermost successive heel lift is marked so that, in driving a nail or other fastening through the successive heel lifts 6, the nails or other fastenings 6^a will coincide with and engage 70 80 the V-shaped cuts or recesses 10 adjacent their crotches. The nails or other fastenings 6^a in engaging with the crotches of the V-shaped cuts or recesses 10 will act to prevent lateral movement of the insert shield. These nails or other fastenings 6^a will penetrate the base or first heel lift and clinch upon a last which may be inserted 85 in the shoe, the nails or other fastenings 6^a acting to not only hold the successive heel lifts in place but also to retain the insert shield in position. The insert shield may be constructed of any suitable metal, preferably 90 galvanized sheet iron or the like.

The rubber heel lift is applied to the last 95 named leather lifts of the heel. The nails or other fasteners which penetrate the rubber heel lift 7 when driven home, contact with and clinch at 8 on the insert shield or plate; therefore, when the rubber heel wears down sufficiently to wear on the fasteners or nails 9, the fasteners or nails 9 will not penetrate the insole of the shoe and prod the foot of the wearer.

In applying the insert shield, plate or 100 protector to shoes now in use, or after the manufacture of the shoes, the heel may be torn down to the first lift which, as stated above, is a continuation of the sole of the shoe. The insert shield or plate is placed 110 in position, as previously stated, and then one or two new leather heel lifts are applied

in the same manner as above stated, then the rubber heel lift is applied, the fastening means or nails of which will contact with and clinch against the insert shield. Obviously when the rubber heel lift wears down, the fastening means or nails 9 will not pass through the inner sole and prod the foot. The insert shield or protector is of arcuate contour in cross sectional area in both directions, that is, dished whereby it may conform to the curvature of the surfaces of the heel lifts.

The invention having been set forth, what is claimed is:

15 The combination with the heel of a shoe comprising a base heel lift and successive

heel lifts, an insert shield or protector plate between the base heel lift and the successive heel lifts, fastening means passing through the successive heel lifts and through the base 20 heel lift, the margin of the insert shield having spaces or cut away portions to permit the fastening means to pass and penetrate the base heel lift, a rubber heel lift adjacent the lower successive heel lift, and 25 fastening means passing through the rubber heel lift and clinching against the insert shield.

In testimony whereof he affixes his signature.

LAWRENCE E. CASSIDY.
